[57] CLAIM

The ornamental design for a data finder, as shown and described.

DESCRIPTION

FIG. 1 is a front elevational view of a data finder showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a bottom, right front perspective view thereof.

FIGS. 1, 2, 5 and 6 have been shown partially broken away for the purpose of indicating indeterminate length.
